his Attorney.

UNITED STATES PATENT OFFICE.

ARTHUR FRISCH, OF BROOKLYN, NEW YORK, ASSIGNOR, BY MESNE ASSIGNMENTS,
TO VOICES INCORPORATED, A CORPORATION OF DELAWARE.

SOUND-PRODUCING DEVICE.

Application filed March 7, 1922, Serial No. 541,757. Renewed April 28, 1925.

This invention relates to sound producing devices, particularly such as are adapted for use in connection with or for insertion in dolls or other toys.

5 The object of my improvements is to provide a device of the class described, simple in construction, having few parts easily assembled and, when assembled, having small liability to derangement. Other objects will 10 appear later herein.

In the drawings accompanying this specification there is illustrated one embodiment of my invention and which is at present the preferred embodiment thereof, for use in the 15 bodies of dolls wherein the sound required is in imitation of the cry of a child and of an intermittent or variable nature. For other toys or other uses, the device may be modified to meet particular environments 20 and requirements, all within the scope of my invention.

Figure 1 is a vertical sectional elevation on line 1—1 of Fig. 2. Fig. 2 is an end elevation looking from the right of Fig. 1. 25 Fig. 3 is a plan view of the bellows element of the device. Fig. 4 is a view similar to that of Fig. 2, showing the operation of the device. Fig. 5 is a sectional elevation, similar to that of Fig. 1, showing a modified 30 form of my improvements. Fig. 6 is a fragmentary front end view, corresponding with Fig. 5. Fig. 7 is a front end view, similar to that of Fig. 6, showing a step in the operation of the device. Fig. 8 is a fragmentary sectional elevation, similar to Fig. 5, 35 showing a further modification of arrangement. All the figures of the drawings are to one scale.

Referring now particularly to Figs. 1 to 40 4 inclusive, my improvements comprise a bellows 3, preferably of ordinary character with two rigid walls 2, 4, articulated along their adjacent ends 2^a, 4^a, and having the usual flexible side walls, as 7, and end wall 45 8. One wall, as 4, of said bellows may be secured to a fixed portion of the device, as wall 9 of a containing case 10. Said case preferably comprises four walls 9, 11, 12 and 13, arranged to form a rectangular box, 50 and end wall 14 closing in one end of said box. The other end of said box or case is preferably provided with a covering 15 of cheese cloth, or the like, adapted for permitting the passage of sound therethrough.

55 Wall 2 of bellows 3, which is herein shown

as the movable wall, is preferably of metal and preferably carries integral therewith reed box 16 having the usual reed 17. Said metal wall 2 and reed box 16 constitute a weight sufficient to actuate the bellows when 60 the device is moved from inoperative to operative position. Said reed box communicates with sound chamber 19 by passage 18. Said sound chamber has the usual "nasal vent" 19^a and in its right hand end, Fig. 1, 65 vent 20, preferably of circular form, from which the sound proceeds, when permitted, and as governed in timing by means presently to be described. Adjacent the path of vent 20, downwardly from the position of 70 Fig. 1, as the bellows movable wall closes, is wall 21 extending across and from top to bottom of the otherwise open end of case 10. Said wall 21 is of peculiar vertical profile, as shown in said Fig. 1, in that one or more 75 portions of said wall, in number corresponding with the number of sound emissions desired during the closing of the bellows, are curved inwardly toward and into the path 22 of vent 20. The major portion of wall 21 80 is preferably of rigid sheet material and may be provided with openings, as 23, 24, therethrough at those portions which project into the path of vent 20. Said openings are covered with flexible sheet material 25, such as 85 rubber, and in the path of said vent, slits 26, 27 are cut through said sheet 25. Said slits are preferably vertical, and normally closed. Said slitted flexible sheet is in the nature of a gate or gates and which slits when open 90 provide a passage for the sound emitted through vent 20.

The operation of this embodiment of my improved device will be understood from the showing of Fig. 4, wherein vent 20 is in engagement with that portion of flexible sheet 25, over opening 23, and has forced forwardly and apart the opposite edges of slit 26, thereby providing a free passage for the air and the sound caused thereby from said vent 20 to without said wall 21 when said sound is audible. As said vent descends further, it will pass from engagement with that portion of flexible sheet 25 over opening 23, whereupon slit 26 will close to the position of Fig. 2, thus shutting off the free passage of air and audible sound to the outside, and vent 20 will presently pass into engagement with that portion of flexible sheet 25 over opening 24 and force forwardly and apart 105 110

the opposite edges of slit 27, thereby providing a passage for the air and sound from said vent, all as just described in relation to slit 26, any sound emitted during the passage of vent

5 20 from opening 23 to opening 24 being confined and inaudible. Then upon the further descent of said vent, slit 27 will close. Auxiliary vent 19^a allows slow ingress or egress of air during the times when vent 20 may be 10 closed while passing into or out of engagement with said gates.

In the modification of Figs. 5 and 6, vent 20 is preferably of rectangular contour and of a width nearly equal to that of bellows 15 movable wall 2. End walls 28, 29 of the vent nose are preferably curved outwardly, so that when gate 25^a of flexible sheet material, is secured thereto and to the upper and lower edges of the vent nose to cover 20 said vent, said gate has an approximately cylindrical contour. Lying centrally said cylindrical contour and transverse said movable wall 2 is slit 26^a of elongated lozenge shape, normally open at its trans- 25 verse mid-portion. Adjacent the path of vent nose 20, downwardly from the position of Fig. 5, as the bellows movable wall closes, is gate operating means 30 for closing said slit 26^a. Said means may comprise 30 a piece of wire conveniently attached at top and bottom, or either, to case 10. Said wire has a vertical profile, Fig. 5, very similar to the profile of wall 21 of Fig. 1, having portions 23^a, 24^a projecting into the path 35 of gate 25^a, whereby, when said gate engages one of those portions, as 24^a, see dotted position Fig. 5, also Fig. 7, the edges of lozenge shaped slit 26^a are forced together, thereby closing gate 25^a against the 40 emission of sound.

The modification of Fig. 8 is very similar to that of Figs. 5, 6 and 7, except that gate 25^b of Fig. 8 is preferably in a plane rather than curved cylindrically outwardly, as in 45 Figs. 5, 6 and 7, and slit 26^b is normally closed, as in the dotted position of Fig. 8, the edges thereof being forced inwardly and apart, see Fig. 8, as said gate encounters an inwardly projecting portion of gate operating wire 30^a.

The operation of the modification shown in Figs. 5, 6, and 7 is similar to that described in connection with the showing of Figs. 1, 2, 3 and 4, except that in said modification the gate is mounted on the movable member instead of on the fixed member, and intermission of audible sound is caused by the closing of said gate during its engagement with the projecting portions of the 50 fixed member.

In the operation of the modification shown in Fig. 8 the gate is normally closed and intermittent sound is emitted as said gate comes into engagement with the projecting portions of yieldable member 30^a,

auxiliary vent 19^a allowing the bellows to continue its movement when said gate is closed.

I claim:

1. In a device of the character described 70 the combination of a bellows having a movable wall, means for moving said movable wall when said device is moved from inoperative to operative position, air actuated sound producing means carried by said movable wall, a vent in said wall for the emission of sound, a gate of flexible material having a slit therethrough, said slit when open providing a passage for sound, and gate operating means for opening or closing said slit as the case may be, said gate and its operating means being relatively movable, one of said elements being carried by the bellows movable wall. 75

2. In a device of the character described 80 the combination of a bellows having a movable wall, means for moving said movable wall when said device is moved from inoperative to operative position, air actuated sound producing means carried by said movable wall, a vent in said wall for the emission of sound, and a fixed gate of flexible material, said gate having a slit normally closed and arranged to be opened by said movable wall vent during the closing 90 of the movable wall. 95

3. In a device of the character described 100 the combination of a bellows having a movable wall, means for moving said movable wall when said device is moved from inoperative to operative position, air actuated sound producing means carried by said movable wall, a vent in said wall for the emission of sound, and a fixed gate of flexible material; said gate having a plurality 105 of slits normally closed and arranged to be successively opened by said movable wall vent during the closing of the movable wall.

4. In a sound producing device the combination of an air chamber with a relatively 110 fixed head and a head movable toward and from the fixed head, a sound reed operated by air forced thereby by movement of the movable head with respect to the fixed head, and means for interrupting and controlling 115 the sound from said sound reed comprising a member of flexible material with an opening therein through which the sound is adapted to issue and means automatically causing said opening to assume open and closed positions responsive to movement of the movable head with respect to the fixed head, said opening in its closed position being entirely closed by said flexible material. 120

5. In a sound producing device the combination of a bellows, a sound reed operated thereby, means for interrupting the sound from said sound reed comprising a member of flexible material which is slotted to form 125 an opening therein through which the sound 130

is adapted to issue, and means causing said slitted opening to be opened and closed responsive to operation of the bellows.

6. In a sound producing device the combination of an air chamber with a relatively fixed head and a head movable toward and from the fixed head, a sound reed operated by air forced thereby by movement of the movable head with respect to the fixed head, and means for interrupting and controlling the sound from said sound reed comprising a member of resilient material with an opening therein through which the sound is adapted to issue, said opening being normally closed by the resiliency of the material itself, and means causing said opening to assume open and closed positions responsive to movement of the movable head with respect to the fixed head.
7. In a sound producing device the combination of an air chamber with a relatively fixed head and a head movable toward and from the fixed head, a sound reed operated by air forced thereby by movement of the movable head with respect to the fixed head, and means for interrupting and controlling the sound from said sound reed comprising a member of resilient flexible material which is slitted to form an opening therein through which the sound from the reed is adapted to issue, said opening being normally entirely

closed by said flexible resilient material and means automatically causing said opening to assume open and closed positions responsive to movement of the movable head with respect to the fixed head.

8. In a sound producing device the combination of a bellows, a sound reed operated thereby, means for interrupting the sound from said sound reed comprising a member of flexible material which is slitted to form an opening therein through which the sound is adapted to issue, said opening in its closed position being entirely closed by said flexible material, and means causing said slitted opening to be opened and closed responsive to operation of the bellows.

9. In a sound producing device the combination of a bellows, a sound reed operated thereby, means for interrupting the sound from said sound reed comprising a member of resilient material with an opening therein through which the sound from the reed is adapted to issue, and means causing said opening to assume open and closed positions responsive to the operation of the bellows, said opening in its closed position being entirely closed by said flexible material.

In witness whereof, I hereby affix my signature this 6th day of March, 1922.

ARTHUR FRISCH.
